UNITED STATES PATENT OFFICE.

THEODORE C. KNAUFF AND HENRY R. HEYL, OF PHILADELPHIA, PENNSYLVANIA;
SAID HEYL ASSIGNOR TO SAID KNAUFF.

TOOTH-BRUSH.

1,175,275.

Specification of Letters Patent. Patented Mar. 14, 1916.

Application filed September 25, 1915. Serial No. 52,545.

To all whom it may concern:

Be it known that we, THEODORE C. KNAUFF and HENRY R. HEYL, both citizens of the United States, residing at Philadelphia, in the county of Philadelphia and State of Pennsylvania, have invented certain new and useful Improvements in Tooth-Brushes, of which the following is a specification.

10 This invention consists in improvements in tooth brushes in which the brush-head portion is detachably secured to the handle member in such a simple method that a new brush, or brushes, of different construction, 15 may be readily detached from the handle and others substituted at will.

The chief objects sought are those of sanitation, extreme simplicity and economy in cost, so that an infected or worn brush may 20 be discarded and a new one substituted, whenever desirable.

In the drawings Figure 1 is a perspective view of the device; Fig. 2 is a plan view of the device with the brush-head inserted and 25 held therein; Fig. 3, a plan view of the holder; Fig. 4 a detail perspective view of the brush-head and Fig. 5 is a cross-sectional view of the brush as held between the side-bars of the handle.

30 Letters of like name and kind refer to like parts in each of the figures.

In carrying out the invention the handle *a* is preferably made from non-corrosive metal wire, formed of one piece bent into a shape 35 that will hold the brush-head *b* firmly, being without joints or crevices in which dirt may lodge, or germs of infection accumulate, and yet at the same time be capable of holding a brush of simplest construction securely; 40 and easily removable by the fingers alone. The said handle *a* must be one that can be easily kept safely sterile so that only the brush-head *b* need be removed.

The brush-head *b* may be made of celluloid, hardwood, rendered water-proof, or of any other suitable material which should be no longer in size than is necessary to hold the bristles, or their substitute, properly, and it should be without openings or crevices 50 other than the shallow grooves *c* along its edges to partially embrace the side bars *d* of the handle *a*.

The handle *a* as shown is made of wire bent to form an elongated loop having its 55 free ends connected at the holding end by

clamping as shown at *e*, or they may be riveted, soldered or otherwise firmly united.

The side bars *d* of the handle *a* from about the middle of their length to the holding end are normally parallel to each other and are 60 separated just enough to allow the brush-head *b* to pass freely between them. At, or near, the middle of the loop the side bars *d* are bent toward each other to reduce the space between them to a width a little less 65 than the minimum width of the brush-head *b* between the bottoms of their grooves, and from this bend to the brush end of the loop the space between the side bars *d* is gradually increased until at the end of the loop it 70 is just as wide as the brush-head *b* at the bottom of its grooves.

By placing the brush-head *b* within the loop at the wide end thereof and sliding it along, the side grooves *c* soon engage with 75 the side bars *d* where they begin to bend and the bars are thus caused to spring apart to admit of the passage of the brush toward the narrow end of the loop when by reason of the spring tension of the resilient loop 80 the brush is held firmly against displacement under ordinary usage.

It will be readily understood that the flexible side bars *d* of the unbroken loop form a reliable pinching contact with the brush-head *b* that is sufficient to hold the latter firmly in place without the aid of any other locking device, and yet the brush may be easily removed from the handle loop by sliding it along to the widened end thereof, 85 where it can drop out.

Having described our invention, what we claim as new and desire to secure by Letters Patent, is:

1. As an improved article of manufacture, 95 a separable tooth-brush, comprising a brush-carrying head; the back member of which has concave grooves along its opposite long edges, in combination with a separable handle formed of a wire loop between the 100 side bars of which the brush-head is removably yet securely held by compression between said side bars of the loop handle, without the aid of other locking device, substantially as described.

2. A handle for a separable brush consisting of an elongated endless wire loop between the resilient side-bars of which a brush may be securely and removably held by pressure alone, substantially as described. 110

3. A handle for a separable brush consisting of an elongated endless wire loop between the flexible side bars of which a brush-head, having concave grooves as shown, may be inserted and retained in place, substantially as described.
4. A handle for a separable brush consisting of an elongated endless wire loop with relatively spaced side-bars forming two openings of different widths, each approximately about one-half the length of the entire loop; whereby a brush-head may freely

enter the wider opening and be passed along into the narrower opening to be there securely held by the clamping effect of the side-bars, substantially as described.

In testimony whereof we affix our signatures in presence of two witnesses.

THEODORE C. KNAUFF.
HENRY R. HEYL.
